Patented Jan. 22, 1974

230,029

PICTURE-SOUND RECORDING APPARATUS

Dennis Knife, Wantagh, and Bernard A. Stone, New York, N.Y., assignors to Syncro-System Corp., New York, N.Y.

Filed Aug. 21, 1972, Ser. No. 282,149

Term of patent 14 years

Int. Cl. D14—01

U.S. Cl. D26—14 B

FIG. 5

FIG. 1 is a front perspective view at the picture-sound recording apparatus;

FIG. 2 is a side view thereof;

FIG. 3 is a rear view thereof;

FIG. 4 is the opposite side view of FIG. 1; and

FIG. 5 is a top plan view.

We claim:

The ornamental design for a picture-sound recording apparatus, as shown and described.
